UNITED STATES PATENT OFFICE.

JAMES E. WITHROW, OF LOS ANGELES, CALIFORNIA.

DESIGN FOR A BEAM FOR LETTER-SCALES.

SPECIFICATION forming part of Design No. 23,335, dated June 5, 1894.

Application filed November 27, 1893. Serial No. 492,151. Term of patent 14 years.

To all whom it may concern:

Be it known that I, JAMES E. WITHROW, a citizen of the United States, residing at Los Angeles, in the county of Los Angeles and State of California, have invented and produced a new and original Design for a Beam for Letter and Package Scales, of which the following is a specification, reference being had to the accompanying drawings, forming part thereof.

Figure 1 is a top view of a beam for a letter or package scale showing my design. Fig. 2 is a side view of a beam for a letter or package scale showing my design. Fig. 3 is a longitudinal sectional view. Line 3—3 Fig. 1 indicates the line of section. Fig. 4 is an end view looking toward the left at Figs. 1 and 2.

In my design for scale beam the side comprises an oblong body tapering in thickness toward one end and having notches along its under edge and an upward projection at one end.

In the drawings A indicates the body of the scale beam.

25 B indicates the upward projection.

C indicates notches along the lower edge of the side of the body of the beam. The top of the scale beam (as shown in Fig. 1), embodying my design, is in plan a plain rectangle while the side (as shown in Fig. 2) is 30 tapering toward the upward projection B and the notches are arranged along the under edge intermediate the ends of the beam and nearer to the narrower end than they are to the broader end.

35 The characteristic features of my design are the tapering body, the notches along the under edge and the upward projection at one end.

Now having described my invention, what 40 I claim as new, and desire to secure by Letters Patent, is—

The design for a beam for letter and package scales substantially as herein shown and described.

JAMES E. WITHROW.
